UNITED STATES PATENT OFFICE.

LOUIS W. SCHNEPP, OF HUNTINGTON BEACH, CALIFORNIA, ASSIGNOR OF ONE-HALF
TO LEWIS F. DAVIS, OF HUNTINGTON BEACH, CALIFORNIA.

WATER HEATER.

Application filed April 2, 1923. Serial No. 629,264.

My invention relates to a water heater of the type generally used for domestic purposes and which is heated by the combustion of gas or liquid hydrocarbon.

5 The principal objects of my invention are, to generally improve upon and simplify the construction of the existing forms of similar water heaters, to provide a water heater that will not, in operation, deposit lime, scale or incrustations upon the metal surfaces with which the water, while being heated, comes in contact, and further to produce a water heater that is characterized by inherent simplicity, low cost of production, minimum fuel consumption and rapidity of operation.

With the foregoing and other objects in view, my invention consists in certain novel features of construction and arrangement of 20 parts that will be hereinafter more fully described and claimed and illustrated in the accompanying drawings in which:

Fig. 1 is a vertical section taken through the center of a water heater of my improved 25 construction.

Fig. 2 is an enlarged horizontal section taken on the line 2—2 of Fig. 1.

Fig. 3 is an enlarged vertical section of 30 a baffle member that is located in the heat flue of the heater.

Fig. 4 is a vertical section taken through the center of the burner that forms a part of my improved water heater.

Fig. 5 is a horizontal section taken on 35 the line 5—5 of Fig. 4.

Referring by numerals to the accompanying drawings, 10 designates a substantially cylindrical, upright tank that is supported by a suitable base 11 and having at its lower 40 end, a burner chamber 12.

The wall of the tank to one side of the burner chamber is provided with an opening 13 that is normally closed by a door 14.

An opening 15 is formed in the center of 45 the head 16, at the lower end of the tank and secured to said lower head around said opening is the lower end of a tube 17.

This tube forms the head flue of the heater and it extends upwardly through the center of the tank and its upper end projects a short distance above the center of the head 18 at the top of said tank.

Spirally disposed upon the tube 17 is a 50 wire 19, the coils of which are spaced three or four inches apart and enclosing said

spirally disposed wire and fitting snugly thereupon is a tube 20. As is shown in the drawing the coiled wire 19 snugly engaging the flue 17 around which it is coiled and also snugly fitting within the tube 20 60 serves to support said tube on the flue.

The lower end of this tube 20 terminates three or four inches above the head 16 and likewise the upper end of said tube terminates a few inches below head 18. 65

Thus both ends of tube 20 are open and in communication with the water space within the tank and the arrangement of the wire 19 between the tubes 17 and 20 forms a narrow spirally disposed duct or 70 passageway 21 around the centrally arranged heating flue, which duct extends from the lower portion of the water space within the tank to the upper portion of said space. Thus water that enters the lower 75 end of the spirally disposed duct or passageway will be heated in its travel upwardly through said duct or passageway, and the heated water will discharge from the upper end of said duct at a point adjacent to the top of the tank and in a plane just below the water level therein.

Suitably supported within tube 17 is an axially arranged rod 22 and positioned thereon and suitably spaced apart are inverted cone shaped baffle members 23. 85

These baffle members are designed to direct the heated air and products of combustion that rise through the tube 17, outwardly against the inner surface of said tube. 90

Leading from the upper end of tube 17 is a stack or vent pipe 24.

Leading from a suitable source of water supply through the upper head 18 of the tank and downwardly through the latter, is 95 a cold water supply pipe 25 and leading from the upper end of the tank is a pipe 26 that conveys the heated water to the points of use.

The burner utilized with my improved 100 water heater and which is illustrated in detail in Figs. 4 and 5 includes a tubular burner body 27 that is slotted lengthwise to form a series of narrow jet openings 28.

Positioned on top of this body is a cap 105 29 and arranged within the tubular body and spaced a slight distance from the inner surface of the wall thereof is a tubular member 30 of reticulated material, preferably fine wire netting. 110

This reticulated member serves to effect a thorough mixing of the gas and air passing through the burner body and to prevent dust and like foreign substance from entering the slots 28.

The lower end of the burner body is connected by a reducing nipple 31, to the upper end of a small tubular member 32 having a flaring or bell-shaped lower end 33.

10 Arranged on the end of a gas supply tube 34 that enters the chamber 12 is a gas regulating valve 35 having a jet nozzle 36 that projects upwardly into the bell-shaped lower end of tube 32.

15 The burner is suitably supported in the lower end of the tubular flue 17 as clearly illustrated in Fig. 1.

Gas issuing from jet nozzle 36 flows upwardly through tube 32, thereby drawing air into the bell-shaped lower end of said tube, which air mixes with the gas and produces a highly combustible mixture that burns upon issuing from the narrow slots 28 in the body of the burner.

25 The heated air and products of combustion from the burner pass upwardly through tube 17 and the baffle members 23 therein, tend to deflect said heated air and products of combustion outwardly against the inner

30 surface of said tube.

Thus as said tube is heated throughout its entire length the relatively thin wall of water immediately surrounding said tube, or the water within the narrow spirally disposed chamber 21 will be rapidly heated, thereby producing a circulation of the water through said chamber 21, from the open lower end of the enclosing tube 20 to the open upper end thereof.

40 The water thus heated is discharged into the upper portion of the chamber within tank 16 and simultaneously, the relatively cool water will be drawn from the lower portion of said chamber into the open lower end of the spirally disposed duct 21.

Obviously the body of water in the tank 10 absorbs a certain amount of heat from the thin volume of water traversing the spiral duct 21 and this absorption or transfer 50 of heat units materially increases the rapidity with which the entire body of water is heated.

55 My improved water heater is designed to function only for the heating of water and not for the generation of steam, and for this reason and the fact that the heating flue and the thin wall of water that directly surrounds said flue are surrounded by a relatively large body of water, there is an entire absence of lime deposits or incrustations 60 on the surfaces with which the water makes contact.

65 In the operation of my heater, it is to be noted that the volume of water contained at any one time within the spiral duct is small

as compared with the total volume of water in the tank and the total volume of water eventually to be completely heated to a predetermined temperature. In heaters that embody simply a tank and a flue extending 70 through it, the whole body of water is virtually heated at one time; that is, the whole body of water is slowly and gradually heated from normal temperature up to the predetermined temperature desired for the 75 hot water, and consequently no hot water at the desired temperature can be withdrawn from the tank until the whole body is heated to that temperature.

In tank heaters, it is impractical and un-economical to supply sufficient heat to raise the whole body of water to the desired hot water temperature in a short period of time—usually the time period is fifteen to twenty minutes or more. In my construction it will be noted that the water is heated in the spiral duct in comparatively small quantities and thus small quantities are, therefore, heated to a comparatively high temperature. The spiral duct, restricted but 80 uninterrupted keeps this small body of water in direct contact with the heating flue long enough to heat it to or somewhat above the hot water temperature desired. The water, which flows by convection through the 85 spiral duct, flows smoothly and uniformly and discharges smoothly and uniformly into the upper part of the tank, and, of course, into the water in the upper part of the tank, the tank always being full of water. This 90 uniform flow of hot water into the upper part of the tank does not materially disturb the upper part of the water body, and does not agitate the water body as a whole. The result, therefore, is that cold water is drawn 95 from the bottom of the tank, passed through the spiral duct, heated and delivered into the upper part of the tank where it remains. As the heating progresses, the hot water line, so to speak, moves down in the tank until 100 the whole tank is heated. At any time, however, a small quantity of hot water, as thus delivered into the upper part of the tank, can be drawn off from the upper part of the tank, but it is not necessary to wait until 110 the whole body of water has been heated to the desired hot water temperature.

Thus it will be seen that I have produced a household water heater that is of relatively simple structure, capable of being easily 115 and cheaply produced and which may be economically used for the comparatively rapid heating of water.

It will be understood that minor changes in the size, form and construction of the 120 various parts of my improved water heater may be made and substituted for those herein described without departing from the spirit of the invention, the scope of which is set forth in the appended claim.

I claim as my invention:

In a water heater, the combination with a vertically disposed tank having a central opening in its top and bottom ends and means for maintaining the tank full of water, of a heating flue vertically positioned within the tank and having communication with said open ends, said flue having uniform diameter throughout its length, an open-ended tubular member having a diameter slightly greater than the diameter of the flue arranged within said tank and enclosing the greater portion of the flue with its ends terminating at a point spaced a substantial distance from said ends of the tank, a combined spacing, partition and tube supporting member spirally arranged within the

narrow space between the flue and tube and engaging said flue and tube whereby to support the tube on the flue and dividing said space into a continuous restricted water circulating duct that extends from the open lower end of the flue-enclosing tube to the open upper end thereof, whereby all of the water entering the lower end of said duct may flow uninterrupted from the lower portion of the body of water in the tank to the upper portion of said body of water, and a burner extending through the opening in the lower end of the tank and into the lower end of the flue.

In testimony whereof I have signed my name to this specification.

LOUIS W. SCHNEPP.
